Teletype Corporation, Chicago, Ill., a corpora-
tion of Delaware

Application June 23, 1949, Serial No. 100,895

7 Claims. (Cl. 178—22)

1

This invention relates to secret communication systems and more particularly to secret printing telegraph systems. Still more particularly the invention deals with an arrangement for communicating information in either plain or enciphered form.

The present invention contemplates the use of a ciphering maze of the type shown in either of the United States Patents 1,861,857 and 1,510,441 issued to E. H. Hebern. The maze may consist of any number of code wheels, each of which will be wired differently. The more code wheels utilized in the ciphering maze, the greater the security; however, the actual number of code wheels in the ciphering maze is immaterial for the purposes of the present invention. Besides the fact that each code wheel is wired differently, each is also wired so that there will be no signal reversals. In some ciphering systems, for example, when a particular character such as the letter "A" is enciphered, the corresponding enciphered character might be the letter "Y" and the coding apparatus is such that the letter "Y" will be enciphered as the letter "A." This type of a system renders the apparatus more simple but has the disadvantage of also facilitating the breaking of the cipher. The maze contemplated for use in the present invention might encipher the letter "A" as the letter "Y"; however, it would only be a random coincidence that the letter "Y" would be enciphered as the letter "A" by the same settings of the code wheels. Therefore, it is apparent that in order to decipher enciphered signals it is not only necessary that the code wheels occupy the same settings for both operations, but also that, in the deciphering operation, the signals pass through the ciphering maze in a direction opposite to that for the enciphering operation.

Accordingly, a principal object of the present invention is to provide means for causing the signals to pass through the ciphering maze in opposite directions for deciphering and enciphering operations.

Another object of the present invention is to provide a secrecy system wherein messages are normally handled in an enciphered condition but which may be handled in plain text or clear condition so long as the operator maintains a special key or switch depressed.

A further object of the present invention is to provide a system in which each station is in condition normally for receiving messages, but which, upon the actuation of a transmitter thereat, is automatically placed in transmitting condition.

2

In the present invention a manually operable push button switch, upon actuation, is designed to control six contact swingers or poles in unison. In one position of the push button all the poles are in "plain text" position, whereas all of the poles are in "cipher" position when the push button occupies its other position. When the system is in "plain text" condition the line circuit extends directly through the local receiver and transmitter to thereby enable transmission and reception in the clear.

When it is desired to carry on communications in "cipher" the switch is placed in "cipher" position. As a result the line circuit no longer extends directly through the local printer and transmitter, and the incoming signals are directed instead through a receiver in the ciphering unit and thence to an outgoing line to complete the line circuit. These signals are deciphered by the ciphering unit and transmitted in "plain text" condition by a transmitter associated with the ciphering unit to the local printer. The ciphering unit is normally in condition for receiving enciphered signals from the line and for deciphering these signals for retransmission in "plain text" to the local printer. When it is desired to transmit enciphered signals over the outgoing line from the local transmitter, such signals are transmitted in "plain text" to the receiver in the ciphering unit. An extra cam on the local transmitter cam shaft is designed to cause the opening of four contacts and closure of five contacts during transmission by the local transmitter. The fifth of these contacts is in circuit with a pair of reversing relays and causes the circuits through the ciphering maze to be reversed so as to enable "enciphering" of signals from "plain text" to "cipher." The remainder of the contacts, upon actuation, place the transmitter associated with the ciphering unit in the line circuit and the ciphering unit receiver in the local circuit.

In addition to the objects above enumerated other objects and advantages of the invention will be apparent from the following detailed description when read in conjunction with the appended drawings wherein:

Figs. 1, 2, and 3 represent a schematic view of the invention;

Fig. 4 shows how Figs. 1, 2, and 3 should be arranged; and

Fig. 5 is a schematic view of a loop circuit in which the present invention is applicable.

It is to be borne in mind that the drawings show the apparatus at but a single station, it be-

ing considered unnecessary to show or describe more than a single station inasmuch as all stations on the circuit are identical. The circuit in which all stations are connected is of the type commonly known as a loop circuit represented by reference numeral 9 in Fig. 5; that is, all stations 10 are in series with one another, with each station having what is conveniently referred to as an incoming line and an outgoing line.

With reference to Figs. 1, 2, and 3 of the drawings reference numeral 11 represents a local printing receiver of any well known type and reference numeral 12 designates a transmitter, preferably of the keyboard type, but of any well known design. Reference numeral 13 designates a selective control unit of the type disclosed in the copending application for patent of W. J. Zenner Serial No. 739,747, filed April 7, 1947. For a detailed description of this selective control unit 13, reference should be made to this application of W. J. Zenner which is hereby incorporated into and made a part of the present specification by reference. A ciphering unit is represented schematically and generally by reference numeral 14, the ciphering unit 14 however being deemed to include the selective control unit or receiver 13 as well as a transmitting distributor represented generally by reference numeral 16. It is to be understood that these units are referred to as specific types of units simply for convenience and it is contemplated that other units capable of performing the functions could be used without departing from the spirit or scope of the invention.

A six pole double throw spring return push button switch 17, having poles 18, 19, 21, and 22, is normally retained in its downward or "cipher" position by means of a compression spring 25. With the switch 17 in its "cipher" position its poles 18, 19, 21, and 22 engage contact points 23, 24, 26, and 27 respectively. When the switch 17 is moved upwardly to its "plain text" position, the poles 18, 19, 21, and 22 engage contact points 28, 29, 31, and 32 respectively.

The transmitter 12 has a transmitting cam shaft 33 on which is mounted the usual stop cam 34 and five transmitting cams 36. When no signals are being transmitted by the transmitter 12 the stop cam 34 retains its contact 37 closed against a contact bar 38. During transmission of signals by the transmitter 12 the cams 36 close their contacts 39 sequentially and permutably according to the signals to be transmitted.

When it is desired to transmit and receive in "clear" or "plain text" the switch 17 is moved upwardly causing the closure of the poles 18, 19, 21, and 22 respectively with the contacts 28, 29, 31, and 32. Under this condition a circuit is established from the incoming line over the pole 21, through the contact points 31 and 29, through the pole 19, over a lead 41, through a selector magnet 42 in the receiver 11, over a lead 43, through either the contacts 37 or 39, through the contact bar 38, over a lead 44, through the pole 18 and contact 28, over a lead 46, through the contact 32 and pole 22, to the outgoing line. Under this condition incoming signals are received in "plain text" condition by the selector magnet 42, the circuit through the transmitter 12 passing through the stop contact 31. When the transmitter 12 operates under this condition the circuit obviously is through the selector magnet 42 and the locally generated signals are therefore printed by the receiver 11.

A cam 47 secured to and rotatable with the

shaft 33 has a high portion 48 which oscillates a follower 49 as the shaft 33 rotates. The follower 49 has five poles 51, 52, 53, 54, and 56 which, when moved to the right, as shown, occupy their receiving position, the poles 51, 52, 53, and 54 respectively engaging contacts 57, 58, 59, and 61 under this condition. As the shaft 33 rotates during the transmission of a signal by the transmitter 12, so as to permit the follower 49 to go off of the high portion 48 of the cam 47, the follower 49, and its poles 51, 52, 53, 54, and 56 move to the left and thereby engage respectively the contacts 62, 63, 64, 66, and 67.

Two poles 166 and 167 are also operable with the switch 17 in the same manner as the poles 18-22. When the switch 17 occupies its upper position, that is, when transmission and reception is being handled in "clear" a circuit extends from battery 168 through a contact 169, over the pole 166, over a lead 171, through a selector magnet 71 in the selective control unit 13, over a lead 172, through the pole 167, through a contact 173, to the battery. Thus battery is maintained on the selector magnet 71 continuously during "clear" transmission.

When signals are being received in "cipher," while the switch 17 occupies the position shown, they pass over a circuit from the incoming line, over the pole 21, through the contact 26, over a lead 68, through the closed contact 57 and pole 51, over a lead 69, through a contact 174 and the pole 166, over the lead 171, through the selector magnet 71 in the selective control unit 13, over a lead 172, through the pole 167 and a contact, over a lead 72, through the closed pole 53 and contact 59, over a lead 73, through the closed contact 27 and pole 22, to the outgoing line. When signals are being transmitted by the transmitter 12 under "cipher" conditions the signals generated thereby are also impressed upon the selector magnet 71 in the selective control unit 13. During the generation of signals by the transmitter 12 it will be noted that the follower 49 moves off the peak 48 to the low portion of the cam 47 while the contacts 39 close sequentially and permutably against the contact bar 38, and therefore the poles 51, 52, 53, 54, and 56 respectively engage the contacts 62, 63, 64, 66, and 67. The path taken by the generated signals extends from the transmitter 12, over the lead 44, through the closed pole 18 and contact 23, over a lead 74, through a battery 76, over a lead 77, through the closed contact 64 and pole 53, over the lead 72, through the contact 176 and pole 167, over the lead 172, through the selector magnet 71, over the lead 171, through the pole 166 and contact 174, over the lead 69, through the closed pole 51 and contact 62, over a lead 78, through the closed contact 24 and pole 19, over the lead 41, through the selector magnet 42 in the printing receiver 11, over the lead 43, to the transmitter 12. Thus the transmitted signals are received and printed by the local receiver 11 in "plain text."

When signals are being transmitted by the transmitter 12, under "cipher" conditions, upon closure of the pole 56 with the contact 67, an energizing circuit for a pair of direction relays 79 and 81 is established from the battery 76, over the lead 77, through the closed contact 67 and pole 56, over a lead 82, through the direction relay 81, over a lead 83, through the direction relay 79, over a lead 84 to the battery 76. Upon energization the relays 79 and 81 pull down all of

their armatures 86 and 87 respectively to make with the front contacts 88 and 89 respectively.

When the signals, transmitted from the transmitter 12, are received by the selector magnet 71, a contact pair 91, in the selective control unit, corresponding to the transmitted signal, and a universal contact pair 92 are closed. Upon closure of the contacts 91 and 92 a universal contact 95 momentarily closes. The universal contact pair 92, upon closure, completes an energizing circuit for a stepping magnet 93 of the ciphering unit 14, from positive battery, through the closed universal contact pair 92, over a lead 94, through the stepping magnet 93, over a lead 96, over a lead 97, through a start magnet 98 of the transmitting distributor 16, to negative battery.

It should be noted at this point that during "clear" transmission battery is maintained on the selector magnet 71 continuously and under this condition the universal contact 92 does not close so that the stepping magnet 93 does not step the maze 14 under this condition. Closure of one of the contact pairs 91 at this time completes a circuit from positive battery, through the momentarily closed contact pair 95, over a lead 98, through the selectively closed contact pair 91, over the proper one of a group of leads 99, through the corresponding armature 86 and contact 88 (remembering that the armatures 86 and 87 engage contacts 88 and 89 respectively at this time), over the corresponding lead of a group of leads 101, over the corresponding lead 102, through a maze 103 like that shown in the afore-mentioned patents to E. H. Hebern, over the proper one of a group of leads 104, over one of a group of leads 106, through the proper ones of the front contacts 89 and armatures 87, over the corresponding one of a group of leads 107, through a corresponding one of a plurality of relays 108, over the lead 97, through the start magnet 98, to negative battery. Whichever one of the relays 108 is energized in response to the closure of one of the contact pairs 91 pulls up all of its associated armatures. The armatures associated with each of the relays 108 consist of a locking armature 109 and up to five signal impulse armatures 111, 112, 113, 114, and 115. When the associated locking armature 109 is pulled up by any of the relays 108 a locking circuit is established for such relay from positive battery, over an inner ring 117 in the transmitter distributor 16, through a pair of connected brushes 118 and 119 which cooperate respectively with the ring 117 and a ring segment 121, through the ring segment 121, over a lead 122, through the pulled up locking armature 109 and its associated contact 123, through the previously energized relay 108, over the lead 97, through the start magnet 98, to negative battery.

When the start magnet 98 is energized, an arm 124 of the transmitting distributor 16 carrying the brushes 118 and 119 commences rotating in a clockwise direction. The initial energizing circuit for the relays 108 is of sufficient duration to retain the selected one of these relays energized until the arm 124 rotates sufficiently to bring the brush 119 into engagement with the ring segment 121 and thereafter the aforementioned locking circuit for the relays 108 becomes effective until the brush 119 moves off of the segment 121. The arm 124 also carries another pair of brushes 126 and 127, the brush 127 being designed for engaging a ring 128 and the brush 126

being designed for engaging a start segment 129, a group of five signal impulse segments 131, 132, 133, 134, and 135, and a stop segment 137. A lead 138 connects the No. 1 impulse segment 131 with a plurality of leads 139, each of which is connected with a contact 141 designed to be engaged by the No. 1 impulse armature 111 when the corresponding relay 108 becomes energized. The No. 2 impulse segment 132 is connected to each of the contacts 142 which are cooperable with the armatures 112, by means of a lead 143 and a group of leads 144. Contacts 146 associated with armatures 113 are connected to the No. 3 impulse segment 133 by means of leads 147 and 148, contacts 149 associated with armatures 114 are connected to the No. 4 impulse segment 134 by means of leads 151 and 152, and contacts 153 associated with armatures 115 are connected to the No. 5 impulse segment 135 by means of leads 154 and 156.

As the arm 124 rotates, permutation signals are generated, in accordance with whichever relay 108 is energized, and impressed on the loop circuit over a circuit extending from the incoming line, through the closed pole 21 and contact 26, over the lead 68, through the closed contact 63 and pole 52, over a lead 157, over a lead 158, through whichever permutation of armatures 111-115 are closed with their corresponding contacts 141, 142, 146, 149, and 153, over a corresponding permutation of leads 139, 144, 147, 151, and 154, over a corresponding permutation of leads 138, 143, 148, 152, and 156, through a corresponding permutation of the signal impulse segments 131, 132, 133, 134, and 135, through the brushes 126 and 127, through the ring 128, over a lead 159, through the pole 54 and contact 66 (closed at this time), over the lead 73, through the closed contact 27 and pole 22, to the outgoing line. When the arm 124 rotates beyond the No. 5 impulse segment 135 the brush 119 rotates off of the ring segment 121 and thus the locking circuit for the selected relay 108 is broken. At this time if another signal is transmitted from the transmitter 12 the brush 126, since it engages the stop segment 137, thereby applies a marking or current condition on the loop circuit until the start magnet 98 is again energized by the next signal impressed to the relays 108, over a circuit extending from the incoming line, through the closed pole 21 and contact 26, over the lead 68, through the closed contact 63 and pole 52 (closed at this time because the transmitter 12 is transmitting another signal), over the lead 157, over the lead 158, through the stop segment 137, through the brushes 126 and 127, through the ring 128, over the lead 159, through the closed pole 54 and contact 66, over the lead 73, through the closed contact 27 and pole 22, to the outgoing line.

If the transmitter has no further signals to be transmitted, continuous marking is maintained on the loop circuit over a circuit from the incoming line, through the closed pole 21 and contact 26, over the lead 68, over the closed contact 57 and pole 51, over the lead 69, over the contact 174 and pole 166, over the lead 171, through the selector magnet 71 in the selective control unit 13, over the lead 172, through the pole 167 and contact 176, over the lead 72, through the closed pole 53 and contact 59, over the lead 73, through the closed contact 27 and pole 22, to the outgoing line.

From the above description of a transmitting operation under "cipher" conditions it is appar-

ent that the signals are generated in "clear" by the transmitter 12, printed in "clear" by the local receiver 11, and impressed in "clear" to the selector magnet 71 of the sequence selector unit 13. In response to each signal a selected contact 91 and universal contacts 92 and 95 are closed. The closure of the universal contact 92 completes a circuit to the stepping magnet 93 of the maze 14 whereas closure of the selected contact 91 and the universal contact 95 completes a circuit through the maze 14 and energizes one of the relays 108 representing an enciphered signal corresponding to the "clear" signal transmitted by the transmitter 12. The energized relay 108 pulls up its armatures and by means of the transmitter distributor the enciphered signal is converted to a permutation signal which is transmitted over the loop circuit 9.

It, of course, is to be borne in mind, even though only a few contacts 91, armatures 86 and 87, and relays 108 are shown, that since a five unit code is being used in the invention, there will be thirty-two of each of these contacts, armatures, and relays. Of course if a six or more unit code were used, which it is contemplated will be used when necessary, the contacts, armatures, and relays would accordingly be increased.

In the case where enciphered signals are received at the local station it is necessary that they be deciphered before being impressed to the local receiver selector magnet 42. Under these conditions the transmitter cam shaft 33 is stationary in the position shown in Fig. 1, with the follower 49 on the high portion 48 of the cam 47 and the poles 51-56 occupying their rightward positions as shown. In such case the received signals follow a circuit from the incoming line, through the pole 21 and contact 26, over the lead 68, through the contact 57 and pole 51, over the lead 69, through the contact 174 and pole 166, over the lead 171, through the selector magnet 71, over the lead 172, through the pole 157 and contact 176, over the lead 72, through the pole 53 and contact 59, over the lead 73, through the closed contact 27 and pole 22, to the outgoing line. It will be noted that under these conditions the pole 56 and contact 67 are not closed and therefore the direction or reversing relays 79 and 81 are not energized, and accordingly the armatures 86 and 87 occupy their upward position in engagement respectively with the contacts 161 and 162.

As in the case when the transmitter 12 is transmitting, the received signals impressed to the selector magnet 71 cause the selective closure of one of the contacts 91 and the invariable closure of the universal contact 92 and the universal momentarily closable contact 95. Closure of the contact 92 enables the energization of the stepping magnet 93 as already described. Closure of one of the contacts 91 at this time completes a circuit from positive battery through the momentarily closed contact 95, over the lead 98, through the selected contact 91, over the lead 99 connected to the selected contact 91, through the corresponding armature 86 and contact 161, over the corresponding lead 104, over the path through the code wheels of the maze 103, over the lead 102 determined by the settings of the maze code wheels, through the corresponding contact 162 and armature 87, over the corresponding lead 101, through the corresponding relay 108, over the lead 97, through the transmitter distributor start magnet 98, to negative

battery. It will be noted that the received signals passed through the maze 103 in a rightward direction and during such passage enciphered signals have been deciphered whereas, as it will

5 be recalled, during the enciphering operation of "clear" signals they passed through the maze 103 in a leftward direction, in each case the circuits having been traced from one of the selective contacts 91 to the selected one of the relays 108. Therefore, the selected relay 108 corresponds to a "clear" signal when the local station is receiving under "cipher" conditions. Upon the selection of the relay 108 it pulls up all of its armatures, including its locking armature 109 and its code armatures 111-115. The code armatures 111-115 and their cooperative contacts, upon closure, are in circuit respectively with the signal impulse segments 131-135.

When the arm 124 rotates in response to the 20 energization of the transmitter distributor start magnet 98 a transmitting circuit is established for impressing the deciphered signal to the local receiver 11 over a circuit from the ring 128, over the lead 159, through the closed pole 54 and contact 61, over the lead 71, through the battery 76, over the lead 74, through the closed contact 23 and pole 18, over the lead 44, through the closed contact bar 38 and stop contact 37, over the lead 44, through the selector magnet 42 in 25 the receiver 11, over the lead 41, through the closed pole 19 and contact 24, over the lead 78, through the closed contact 58 and pole 52, over the lead 157, over the lead 158, through the closed permutation or armatures 111-115 and contacts 141, 142, 146, 149, and 153, over the corresponding permutation of leads 139, 144, 147, 151, and 154, over the corresponding permutation of leads 138, 143, 148, 152, and 156, through the corresponding permutation of signal 30 impulse segments 131-135, through the brushes 126 and 127, to the ring 128. When the arm 124 has rotated through a complete revolution and returned to its stop position (as shown) with the brush 126 on the stop segment 137 and with the brush 119 off of the segment 121, the locking circuit for the selected relay 108 is broken and all of its armatures fall away. At this time, until another signal is impressed to one of the relays 108, a marking or energized 35 condition of the local selector magnet 42 is maintained by means of a circuit extending from the ring 128, over the lead 159, through the closed pole 54 and contact 61, over the lead 71, through the battery 76, over the lead 74, through the closed contact 23 and pole 18, over the lead 44, through the closed contact bar 38 and contact 37, over the lead 43, through the selector magnet 42, over the lead 41, through the closed pole 19 and contact 24, over the lead 78, through the closed contact 58 and pole 52, over the lead 157, over the lead 158, through the stop segment 137, through brushes 126 and 124, to the ring 128.

It is therefore apparent that incoming enciphered signals from a distant station are first 40 impressed to the selector magnet 71 in the selective control unit 13. The selective control unit 13, in response, causes one of a plurality of contacts to be selectively closed to thereby complete a circuit through the maze 103 and to a relay 108 which corresponds to the "clear" signal deciphered by the maze 103. The "clear" signal 45 impressed on the relay 108 is then converted to a five unit permutation signal and transmitted by the transmitter distributor 16 over a circuit to 50 the local receiving printer 11.

By the present invention there is provided a ciphering system which is designed to handle enciphered transmission whereby a ciphering unit at a particular station normally functions to decipher incoming signals, but which is automatically rendered effective to encipher transmitted signals. By the slight manual operation of depressing a key, transmission in the "clear" is made possible. It is contemplated that the settings of the code wheels in the ciphering maze at the different stations will be uniform and will be accomplished by any of the methods well known at the present time.

Various changes and modifications may be made without departing from the spirit and scope of the invention.

What is claimed is:

1. In a secret printing telegraph system, a line, a plurality of stations on said line, a ciphering maze at each of said stations, each ciphering maze effective for deciphering received signals in one direction therethrough and enciphering transmitted signals in the opposite direction therethrough, each of said ciphering mazes being in condition normally for deciphering received signals, means at each station operable automatically upon the transmission of a signal therefrom for causing said ciphering maze to encipher said signal, and means operable automatically upon the encipherment of said signal for transmitting the enciphered signal over said line.

2. In a secret printing telegraph system, a line, a plurality of stations on said line, a ciphering maze at each of said stations, each ciphering maze effective for deciphering received signals in one direction therethrough and enciphering transmitted signals in the opposite direction therethrough, each of said ciphering mazes being in condition normally for deciphering received signals, a transmitter at each of said stations for generating plain text signals, means at each station effective automatically upon the generation of a plain text signal by said transmitter for causing said ciphering maze to encipher said signal, and means operable automatically upon the encipherment of said signal for transmitting the enciphered signal over said line.

3. In a secret printing telegraph system, a line, a plurality of stations on said line, ciphering means at each of said stations for deciphering received signals and enciphering transmitted signals, said ciphering means being effective to decipher signals passing therethrough in one direction and to encipher signals passing therethrough in the opposite direction, means associated with each of said ciphering means for controlling the direction of the passage of signals through said ciphering means, and normally effective to cause passage of signals through said ciphering means in said first mentioned direction to thereby cause decipherment of signals, a transmitter at each of said stations for generating plain text signals, means at each station effective automatically upon the generation of a plain text signal for causing said direction control means to cause the signal to pass through said ciphering means in said second mentioned direction to thereby cause encipherment of said signal, and means operable automatically upon the encipherment of said signal for transmitting the enciphered signal over said line.

4. In a secret printing telegraph system, a line,

a plurality of stations on said line, a ciphering maze at each of said stations, each ciphering maze effective for deciphering received signals in one direction therethrough and enciphering transmitted signals in the opposite direction therethrough, said ciphering maze being normally effective to decipher received signals, cipher controlling means for rendering said ciphering maze ineffective to decipher received signals and effective to encipher transmitted signals, means at each station for generating plain text signals, means at each station effective automatically upon the generation of a plain text signal for causing said cipher controlling means to render said ciphering maze ineffective to decipher received signals and effective to encipher said plain text signal, and means operable automatically upon the encipherment of said signal for transmitting the enciphered signal over said line.

5. In a secret printing telegraph system, a line, a plurality of stations on said line, a ciphering maze at each of said stations, each ciphering maze effective for deciphering received signals in one direction therethrough and enciphering transmitted signals in the opposite direction, therethrough, said ciphering maze being normally effective to decipher received signals, relay means for rendering said ciphering maze ineffective to decipher received signals and effective to encipher transmitted signals, means at each station for generating plain text signals, a cam controlled switch at each station effective automatically upon the generation of a plain text signal for causing said relay means to render said ciphering maze ineffective to decipher received signals and effective to encipher said plain text signal, and means operable automatically upon the encipherment of said signal for transmitting the enciphered signal over said line.

6. In a secret printing telegraph system, a line, a plurality of stations on said line, a ciphering maze at each of said stations effective to decipher signals passing through said maze in a first direction and effective to encipher signals passing through said maze in an opposite direction, relay means at each station for controlling the direction of the passage of signals through said maze, said relay means normally enabling signals to pass through said maze in said first direction to cause deciphering, a transmitter at each of said stations for generating plain text signals, a cam controlled switching means at each station effective automatically upon the generation of a plain text signal by said transmitter for actuating said relay means to cause the signal to pass through said maze in said opposite direction, whereby said signal is enciphered, and means operable automatically upon the encipherment of said signal for transmitting the enciphered signal over said line.

7. In a secret printing telegraph system, a line, a plurality of stations on said line, a transmitter at each of said stations for generating plain text signals, a receiver at each of said stations, a ciphering maze at each of said stations, each ciphering maze effective for deciphering enciphered signals in one direction therethrough and for enciphering plain text signals in the opposite direction therethrough, a selective control unit associated with each ciphering maze for receiving plain text signals generated by the transmitter at the same station and for receiving enciphered signals from another station,

75

and for directing both of these types of signals to the ciphering maze associated therewith, relay means at each station normally effective to cause said ciphering maze at the same station to decipher enciphered signals received by the selective control unit thereat, means at each station actuated by said transmitter at the same station upon the generation of a plain text signal thereby for operating said relay means at the same station to cause the ciphering maze to encipher said plain text signal upon its receipt by the selective control unit at the same station, and means operable automatically upon the encipherment of said plain text signal for trans-

mitting the corresponding enciphered signal over said line to the other stations thereon.
